UNITED STATES PATENT OFFICE.

THOMAS J. LOVEGROVE, OF PHILADELPHIA, PENNSYLVANIA.

ARCH.

SPECIFICATION forming part of Letters Patent No. 271,344, dated January 30, 1883.

Application filed May 25, 1881. (No model.)

To all whom it may concern:

Be it known that I, THOMAS J. LOVEGROVE, of the city and county of Philadelphia, and State of Pennsylvania, have invented certain new and useful Improvements in the construction of Arches, of which the following is a specification.

My invention relates to an improved method and devices whereby arches for conduits, sewers, bridges, and other purposes may be constructed of maximum strength with the minimum of labor and material.

In every arch with which I have been heretofore acquainted the tendency is to the production of a number of force-resultants between the crown and the skewbacks—that is to say, the direction of the lines of force or thrust which tend to destroy the structure is tangential to the curve of the arch. Consequently, in order to equalize the strength of the latter, it has been necessary to place a surplus of material of which it is constructed out of line, so that the true line of equipollence shall practically lie between the extrados and the intrados of the voussoirs.

In technical works, and particularly in those relating to the construction of arches and bridges, it is common to see the term "equilibrium" applied to the curve of the arch; but in all cases it is used simply in an approximate sense, as heretofore it has been impossible to accurately construct an equilibrium-arch supporting an unequal load. If we consider the catenary inverted it is not a true equilibrium-arch, unless we imagine the cable without weight, and the greater the weight the greater will be the discrepancy between the arch obtained and the true equilibrium-arch. Heretofore the nearest method for approximating an equilibrium-arch for an uneven load was by considering a chain or cable hung from two points, with the variable loads hung from said cable along its length, and after ascertaining the curve produced the same was inverted and called the "equilibrium-arch" for that unequally-distributed load; but this was only approximate, as where the greatest tension was now we would have the greatest compression, and it is utterly impossible to cause all of the resultant forces to pass down through the skewbacks. The formulas hereto-

fore used for the mathematical calculation and demonstration of the equilibrium-arch are based upon the above facts.

An arch constructed upon the system hereinafter explained has substantially, both theoretically and practically, but two grand resultants—one to the right, the other to the left, from keystone to skewback. Such arch carries its load as absolutely as a plumb column supports the weight upon it. An arch constructed on any other principle has its counterpart in a bent column, the tendency of which is to spring out from the pressure of the superincumbent load. An arch constructed upon the principles now to be set forth enables me to use a movable templet merely, instead of the usual temporary center or support.

I shall now proceed to describe the mode of carrying out my invention, reference being had, as may be necessary, to the accompanying drawings, of which—

Figure 1 is a perspective view of a conduit-arch in process of construction with movable templet. Fig. 2 is an end view thereof, the arch being in section made adjacent to one of the re-enforcing ribs, hereinafter mentioned. Fig. 3 is for reference in illustrating my system for determining the proper form of the arch or arches to be constructed. Fig. 4 represents the mode of applying my invention in the construction of a dome.

I have found by mathematical calculation and by actual experiments that in the curve of a perfect arch of equipollence, be the superincumbent static load upon the arch what it may, the length of the abscissa at any point in such curve is invariably equivalent to the load at such point multiplied by the leverage (from the skewback) and the product divided by the maximum thrust. It is therefore only requisite to find the lengths of the abscissæ, or of a sufficient number thereof for practical purposes, in order to be able to obtain the proper curve of the arch in each special case.

I shall first demonstrate my method of determining the correct form for such an arch of even load.

Upon a base, C N, Fig. 3, equal in length to one-half that of the span or chord of the proposed arch, I erect a right-angled triangle, A C N, whose altitude, A C, is equal to the rise or

versed sine of said arch. In the present illustration the whole span is taken as twenty feet, the rise at ten feet, the figure (3) being to scale of one-half inch to the foot. The weight 5 above and resting upon the points $A, A', A'', \dots$ —ten in all, let it be supposed—of the hypotenuse A, N is represented by the unit 1, whether one pound or one ton is immaterial. Now, bearing in mind the rule above stated, I 10 will show, as an example, how the proper length for the fifth abscissa rising from the point C^5 is obtained. The entire load upon the hypotenuse is 10. The maximum thrust at A is therefore 5. The proportion of weight 15 upon A^5 is 7.5, which multiplied by 5, the leverage from N , (the skewback of the proposed arch,) gives a product of 37.5; this divided by 5, the maximum thrust, gives a quotient of 7.5 feet as the correct length of the abscissa 20 $B^5 C^5$ for the true arch of equipollence of equal load. A similar calculation, starting from any other point in the hypotenuse A, N , will determine the length of the abscissa of the arch passing through such point. Thus the arch Z , 25 of even load, having the thrust the same at every point therein, is laid down by drawing a line, A, Z, N , connecting the summits of the several abscissæ $B', B'', \dots$. The figures in the plane of the Z arrow represent the lengths of 30 ten of the abscissæ of this arch.

I shall now proceed to show the application of my said method in the determination of the form of an arch, Y , of equipollence in the case of unequal load, the chord and rise of the arch being assumed as of the same length, respectively, 35 as before. The space contained by the straight lines F, A, N, E , Fig. 3, is presumed to be filled in with earth or other material of the specific gravity of that which shall be over the arch 40 after it is built. Say, for instance, that this mass of material below the line F, E of the road or street, supported by the hypotenuse A, N , weighs one hundred and fifty pounds to the foot. A simple calculation, which I do 45 not deem it necessary to enter into here, gives five thousand pounds as the theoretical maximum thrust at the point A . Now, taking for illustration the weight or load sustained at the point A^5 , which is found to be 8,125.75, 50 and multiplying the same by the leverage, five feet, the product 40,628.75 results, and this, divided by the maximum thrust, 5,000, gives 8.12+ feet—the proper length of the abscissa $D^5 C^5$ of the true arch Y (in this case) of 55 equipollence. By repeating the foregoing calculation with suitable change of factors required by the rule hereinbefore stated, based from as many other points in hypotenuse A, N as may be thought advisable, the respective 60 abscissa-lengths may be obtained. The lengths of several of the abscissæ of arch Y are given in a line opposite the Y arrow, Fig. 3. It is obvious that the greater number of abscissa-lengths thus found the more nearly 65 the curve will approach the theoretically-perfect arch of equipollence for the special case. Ordinarily it is necessary to determine the

lengths of but a few of such abscissæ. If, however, the work to be constructed is of much magnitude or importance, it is desirable to attain a greater degree of accuracy in the curve 70 of the arch by calculating the lengths of a comparatively large number of abscissæ.

The curve X , Fig. 3, is that of a semicircular arch of the same span and rise as the true arch Y under the same circumstances. This is the most usual form of arches for sewers and many other purposes. The difference between these curves X and Y in the present instance indicates obviously a large quantity of material of the arch built upon the former out of line. In long sewers or conduits the economy in labor and material secured in the construction of my arch over the semicircular or Roman arch is very considerable. The curve of 80 equipollence of the arch, under the special circumstances, having been thus substantially determined, I now construct a corresponding templet, T , of wood or other suitable material, such as is shown in Figs. 1 and 2. This is 85 mounted upon a bed or frame, L , and is provided with a series of platform-steps, P , upon which the masons are supported while building the arch H . The structure is adapted to be easily moved forward horizontally, as desired, upon wheels W , fitted to run upon rails R , which are suitably laid in the line of the intended conduit. In the present instance these rest upon a cross-piece, O , thrown across 90 the lower section of the conduit. The wheels 95 and rails may, however, be dispensed with, and the device be made to slide upon ways fixed at the sides, or upon the bottom of the interior of the conduit, or otherwise.

In building long arches, as for sewers, conduits, &c., the arch-bricks or voussoirs are racked up, as seen in Fig. 1. At the beginning of the arch H , for a short distance, the templet T performs the function of a center or support for the material being laid—that is, 100 until the bricks are racked up on each side, near to the crown of the arch, and the crown-bricks (or keystones) have been driven in place, whereupon the arch springs slightly outward, sufficient to free it from the templet, as 105 seen in Fig. 2, and allow the latter to be moved forward. Thenceforth the arch is self-supporting until its entire length is finished, the bricks being laid racked in close proximity to the templet—not against it. Thus with a 110 templet having its outline formed according to the system hereinbefore explained, and such templet adapted to be shifted, as described, there is no need, as has been heretofore the case, of using the usual rigid centers, which 115 are left in place until the mortar or cement between the voussoirs of the superstructure shall have hardened and the earth or other material be filled in above the arch. Although 120 such arch be designed to carry an uneven load, and built before the load actually comes upon it, yet it will stand, under almost all circumstances, without adventitious support, for 125 the reason that practically the true curve of 130

the arch of equipollence of even load will generally lie somewhere between the intrados and the back of such arch of uneven load. If, however, as in extreme cases, the character of the superincumbent load which is to rest upon the completed arch is such as to demand a curve so far from that of the arch of equipollence of even load that there may be danger of the unloaded arch falling in, I lay upon the main arch H, Fig. 2, a re-enforcing rib or course, J, at suitable intervals. I also employ such re-enforcing ribs in long arches—such as for sewers—in order to counteract the relative weakness due to the length of such structures, for the longer they are the weaker they are with the same thickness of material throughout. I prefer to locate one of said ribs, which need be but two or three feet broad under ordinary circumstances, opposite each house along the route of the sewer, so that connections between the latter and the house-mains may be made through the re-enforcement, thus avoiding or counteracting the weakening of the main arch, which would otherwise result. Such re-enforcing ribs serve also to arrest the damage which might be caused by careless or unskillful workmen in building the sewer.

In constructing domes I first determine the proper outline of a suitable templet according to the principles of the system hereinbefore elucidated, the effect of the lantern, if any, which is to crown the dome, being taken into account in arriving at the several abscissa-lengths of the arch of the dome. I then construct a templet, T, such as shown in Fig. 4. It is provided with a rib, G, of the desired contour, on its exterior edge, and is fixed upon a frame or platform, I, having wheels W, whereby the templet may be rotated upon a center, K, around the circle of the dome in process of construction, from time to time, as may be necessary, as the work of building proceeds. Instead of a single one, several such templet-ribs, supported upon frame I, may be used where a number of masons are at work at as many points in the circumference of the circle of the dome; also, in lieu of such templet, a revolving finger, devised so that it may be swept around and give the proper line upon which to build the dome, may be employed.

A dome constructed according to the principles of my system needs no support while being built.

I claim—

1. The improvement in the art of constructing arches, consisting in racking up the bricks against a center or support at the beginning, and then proceeding by racking up in close proximity to a movable templet, the latter being shifted forward from time to time during the process of building the arch, substantially as and for the purpose set forth. 55

2. The improved method of constructing an arch of equipollence, consisting in racking up the bricks upon a movable templet at the beginning; as upon a center, till near the crown; then driving in the crown-bricks, thereby springing the arch out slightly from the templet; then successively moving the templet forward as the arch is further laid up without bearing 65 upon the templet, substantially as described.

3. The process of constructing an arch, which consists in laying the bricks up against a templet or center until near the crown, and then springing out the arch by forcing in the 75 crown-bricks, thus freeing the arch from the center, substantially as described.

4. In the construction of arches according to the manner or process hereinbefore described, a non-collapsing templet upon guides or ways, 80 and adapted to be gradually shifted while the arch is in process of construction, substantially as and for the purposes set forth.

5. The movable templet T, provided with platform-steps P, substantially as and for the 85 purposes shown and described.

6. In the construction of arches, the voussoirs arranged in curvilinear form, in combination with an ununiform static load located above said voussoirs and supported thereon, said 90 arch being without supporting abutments above its springing points or skewbacks, and having but two resultants which pass down through the skewbacks, substantially as and for the purpose specified. 95

7. An arch, in combination with an unevenly-distributed static load, said arch having but two resultants, coinciding with the line of curvilinear pressure, the abscissa at any point of said arch being equal to the gravity-pressure or static load multiplied by the leverage thereof and divided by the curvilinear pressure or estimated maximum thrust, as set forth. 100

THOMAS J. LOVEGROVE.
